UNITED STATES PATENT OFFICE.

MARTIN L. HERPOLSHEIMER, OF CHICAGO, ILLINOIS.

AIR-PUMP-OPERATING MECHANISM.

1,250,456.

Specification of Letters Patent. Patented Dec. 18, 1917.

Application filed January 6, 1916. Serial No. 70,654.

To all whom it may concern:

Be it known that I, MARTIN L. HERPOLSHEIMER, a citizen of the United States, residing at Chicago, in the county of Cook and State of Illinois, have invented a new and useful Air-Pump-Operating Mechanism, of which the following is a specification.

The present invention appertains to pumps, and aims to provide a novel and improved air compressor adapted especially for use with automobiles for inflating the tires, the device being of novel construction to enhance the utility and efficiency thereof, whereby the air can be compressed and forced into the tires in a convenient yet effective manner.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:—

Figure 1 is a side elevation of the improved pump, portions being broken away and shown in section.

Fig. 2 is a cross section on the line 2—2 of Fig. 1, portions being broken away.

In carrying out the invention, there is provided an elongated base 1, preferably in the form of a casting, and having at its ends upwardly projecting standards 2 to which the remote ends of a pair of alining cylinders 3 are attached in any suitable manner. Pistons 4 work within the cylinders and are connected by a common piston rod 5, whereby the pistons reciprocate in unison in the same direction, one piston moving toward the outer end of its cylinder, while the other cylinder moves toward the inner end of its cylinder, thereby providing a double acting pump.

A longitudinal pipe 6 is terminally attached to the standards 2 above the cylinders 3, and branches 7 connect the pipe 6 and cylinders 3 adjacent the remote ends thereof, to provide outlets for the cylinders leading into the pipe 6, said outlets 7 being normally closed by check valves 8. An outlet branch 56 or nipple 9 projects from the pipe 6, prefer-

ably adjacent one end thereof, and can be connected through the medium of a hose (not shown) or other conductor with the tires or the like. Suitable means are provided whereby air is supplied within the 60 cylinders between the pistons and outer ends of the cylinders when the pistons move inwardly, and this is conveniently accomplished by providing the pistons 4 with air ports 10, normally closed by check valves 11, 65 which check valves open when the pistons move inwardly to thus allow air to flow into the outer chambers of the cylinders.

In order that the base or frame 1 can be clamped upon a running board or other suitable part of the automobile or other support, the base 1 is provided between its ends with a depending L-shaped bracket 12 through the lower arm of which is threaded a clamping screw 13. The base 1 can be 70 placed upon the running board or other support with the bracket 12 projecting under the support, and the screw 13 can then be threaded upwardly to clamp the support between the base and screw, thereby holding 75 the base 1 rigidly in place while the pump is operated.

As a convenient and effective means for reciprocating the piston rod 5, an upwardly projecting hand lever 14 has its lower end 80 fulcrumed, as at 15, to one edge of the base 1 between the ends thereof, and the lever 14 is connected by a link 16 with a shorter upwardly projecting lever 17 having its lower end fulcrumed, as at 18, to the same edge of 85 the base 1 that the lever 14 is fulcrumed to. The lever 14 is relatively long, while the lever 17 is much shorter, in order that a proper purchase can be obtained, and the link 16 is arranged obliquely, one end thereof being spaced farther from the fulcrum 15, than the other end is spaced from the fulcrum 18. Thus, the lever 17 is swung through a larger arc than the lever 14, whereby the swinging movement of the hand lever 14 need not be great. The upper or free end of the short lever 17 is connected by a link 19 with a cross head or block 20 secured upon the rod 5 between the cylinders, whereby the oscillation of the lever 17 will 90 impart a reciprocatory movement to said rod. The cross head 20 has a depending arm 21 provided with an eye 22 slidably embracing a longitudinal guide rod 23 terminally secured to the base 1 between the cylinders, 95 100 105 110

whereby the cross head is mounted for proper sliding movement above the base.

The lever 14 is preferably divided intermediate its ends, and the adjacent ends of the sections are hinged together, as at 24, whereby the lever can be folded or doubled when the pump is not in use, in order that the pump can be stored or transported within small compass.

- 10 In operation, the mechanism for operating the pistons provides for considerable power, by means of the leverage, and upon each stroke of the piston rod 5, air is forced from one cylinder into the pipe 6, thereby providing for a practically continuous flow of air, instead of an intermittent flow as with an ordinary single acting pump. The tires can therefore be inflated much quicker, and without any lost motion, since each
- 15 stroke of the lever or operating member is effective for compressing the air.

The present pump provides a convenient and serviceable one for use in connection with automobiles for inflating tires, although

the pump can be used for various other purposes as well.

Having thus described the invention, what is claimed as new is:

A device of the character described embodying an elongated base, a rod mounted 30 for reciprocation above the base, an upwardly projecting operating lever pivoted to the intermediate portion of the base, a second short lever pivoted to the base between the operating lever and one end of the 35 base and projecting upwardly, an oblique link connecting the two levers, and an oblique link crossing the aforesaid link and connecting the second mentioned lever with the intermediate portion of said rod. 40

In testimony that I claim the foregoing as my own, I have hereto affixed my signature in the presence of two witnesses.

MARTIN L. HERPOLSHEIMER.
